Application November 18, 1932, Serial No. 643,276
In Great Britain November 30, 1931

33 Claims. (Cl. 112—158)

This invention relates to sewing machines, for embroidery or other decorative sewing, of the kind having at least one needle, means for reciprocating the needle axially, means for shifting or throwing the needle to and fro laterally to a controllable or variable extent, a needle thread supply, an under thread supply, and a rotary hook which enters loops formed in the needle thread below the fabric and serves to interengage said loops with the under thread, the needle reciprocating and throwing means and the hook being actuatable in timed relationship.

Known machines of this kind have been capable of satisfactory work within a limited needle throw, which has usually been achieved by mounting the needle-bar for reciprocation in a pivotally suspended carrier and vibrating the carrier through a so-called "cross-over crank" which is reciprocable in a substantially horizontal direction with variable stroke under the machine operator's control exercised through a "knee-lift" lever. The factor that has hitherto limited the extent of throw is the necessity for the rotary hook, which turns in a path of small radius about a fixed centre, to engage the loop formed by the needle below the base fabric in the needle thread, notwithstanding that the successive reciprocations of the needle form loops at different points in the path of the hook. Satisfactory operation has only been achieved over the small upper arc of the hook path where the said path and the line drawn through the lower limits of the needle strokes in different lateral positions have been substantially parallel, and even so, to maintain the time period of the coincidence of the hook and the needle in the sequence of operations substantially unaffected, it has been necessary to employ special mechanism imparting an irregular speed of rotation to the hook despite the limitation of the needle throw. Withal, the known machines are liable to execute faulty work by reason of the hook failing to engage the needle thread loops in the extreme lateral positions of the needle throw.

Now the present invention makes it possible to attain not only certainty of engagement of the needle thread loops by the hook at the heretofore known limits of throw, but optionally a much greater throw, up to about the diameter of the hook path, with the same certainty of operation.

The invention provides means for varying the height at which the needle reciprocates, in dependence on the lateral throw imparted to the needle, in such manner as to ensure proper

presentation of the needle thread loop to the hook in all lateral positions of the needle.

The means for raising and lowering the height of the needle as it is thrown laterally is or may be such that the time taken for the needle in any line of reciprocation to pass and repass the effective arc of the hook path is equal to the time taken by the hook to reach the said line.

The invention also provides means for effecting a lateral throw of the needle up to an extent substantially equal to the diameter of the hook, and means for ensuring proper presentation of the needle thread loop to the hook in all lateral positions of the needle.

Any of the means as aforesaid may be incorporated in a machine designed to comprise them, or any of the said means may constitute an attachment for the existing machines of the kind set forth.

Another disadvantage to which the known machines have been subject heretofore is that the tension on the needle thread has been controlled by a take-up lever and an adjacent friction device from which the thread passes to the lever, so that the tension of the thread has been the same irrespective of the varying throw of the needle. This, even with the limited maximum throw hitherto obtainable, has been objectionable, and in some cases has resulted in "shirring" of the base fabric.

To overcome this defect the invention provides means whereby the tension exerted by the said friction device on the needle thread is automatically decreased or increased inversely with increase or decrease in the lateral shift or throw of the needle, so that the said disadvantage arising from constant thread tension is avoided, and also increased throw of the needle may be employed without the quality of the work being impaired by excessive thread tension.

By way of example the invention will now be described as applied to an existing machine similar to the commercial "Singer Sewing Machine 107w100".

In the accompanying drawings:—

Fig. 1 is a fragmentary elevation of the machine;

Fig. 1a is a fragmentary elevation of certain of the existing details of the machine;

Fig. 1b is a plan view of the said details;

Fig. 2 is an end view of the novel means shown in Fig. 1;

Fig. 3 is a diagram illustrating a feature of the said means;

Figs. 4 and 5 are diagrams illustrating the operation of the said means;

Fig. 6 is an elevation of a constructional form of the hereinbefore mentioned means for automatically varying the thread tension;

Fig. 7 is a sectional elevation on the line VII—VII of Fig. 6;

Fig. 8 is a perspective view of the whole machine head showing the correlation of various known parts thereof with the means according to the invention; and

Fig. 9 is an elevation showing a modification or development of the invention for employing two needles simultaneously.

From the drawings it will be evident to those skilled in the art that many parts of the machine are retained unchanged. However, reference to some of these parts and their function or operation is first necessary in order that the present invention may be clearly understood. The machine head 1 is mounted over the work table 2, and encloses mechanism for operating from the shaft of the flywheel pulley 6 (Fig. 8) the needle-bar 3, the cross-over crank 4 and the rotary hook 5. The head also supports the double presser foot assembly 7, the thread spool mounting 8, the means 9 serving for the initial lateral positioning of the needle, and the linkage system 10, 11, 12, 13 (Fig. 6) serving to transmit the movements of the knee-lift lever (not shown) for controlling the throw of the needle during operation of the machine. The cross-over crank 4 is actuated by the cam 14 (Figs. 1a and 1b) secured to the cross shaft 15 and engaging the fork 16 formed at the end of the crank 4, which end is supported by the link 17 pivoted to the crank at 19. The link 17 is in turn pivoted on the pin 20 carried by the crank 21, which is fast on the shaft 22. The said shaft 22 is turnably mounted in and bodily movable by the link 23, which is itself turnable by the lever 9 (Fig. 6). With this lever in the position shown the stitches are formed to the right of a datum line; when the lever 9 is moved so that the pin 9a thereon engages the aperture 9b, the consequent displacement of the link 23 and shaft 22 causes the stitches to be effected equally on both sides of the datum line; and when the lever 9 is moved so that the pin 9a engages the aperture 9c, the displacement of the link 23 and shaft 22 causes the stitches to be formed to the left of the datum line. The shaft 22 also has secured to it the crank-lever 13 (Fig. 6) movement of which, by the knee-lift lever, through the linkage 10, 11, 12, turns the shaft 22. Thus the crank 21 can be turned to a controllable extent to change the position of the pin 20. When the crank 21 is turned to a position approaching the horizontal, the forked end 16 of the cross-over crank 4 is merely raised and lowered by rotation of the cam 14, the pivot 19 describing a vertical arc about the pin 20, and the horizontal movement imparted to the cross-over crank being very small; but when the crank 21 is turned towards the vertical (as shown in Fig. 1a) the arc described by the pivot 19 acquires a greater horizontal component, the horizontal movement imparted to the cross-over crank 4, and consequently the throw of the needle, being correspondingly increased. The needle is mounted for reciprocation in a swing carrier (not shown) and normally the crank 4 is connected to and so oscillates the said swing carrier.

All the foregoing features are known.

For the purpose of the invention the swing carrier is locked against swinging movement, for

example by a set screw, and, as shown in Figs. 1 to 5, an attachment is provided comprising a plate 24 secured to the needle-bar 3 and having horizontal guides 25 serving to guide a second plate 26. This second plate 26 has vertical guides 27 in which a block 28 constituting a holder for the needle 29 is movable. This block or needle holder 28 has a pin 30 projecting from its back and passing through an aperture 31 in the second plate 26 to enter a cam slot 32 in the plate 24. An anti-friction roller may be provided on the pin to engage the walls of the cam slot. The lateral movement of the needle is now achieved by moving the second plate 26 along the slides 25. The movements of the plate 26 are received, directly or indirectly, from the cross-over crank, the end of which is constrained to reciprocate in a horizontal, lateral line by guides 35, 36, 37 on the body of the machine, and a pin 38 mounted in a lug on the said body.

To the attainment of the possibility afforded, by the means just described, of increasing the lateral throw of the needle substantially up to the diameter of the path of the hook 5, a short connecting link 33 is pivoted to the cross-over crank 25 at 34, and transmits the horizontal movement thereof, through a pivotal connection 39, to a multiplying lever 40. This lever 40 is pivoted at 41 to the body 1 of the machine and at 42 to a block 43 through which extends, with a sliding fit, a vertical rod 44 projecting upwardly from a lug 45 forming part of the second plate 26. The sliding engagement of the block 43 and the rod 44 enables the plate 26 to be moved laterally through the link 33 and the lever 40 notwithstanding that the plate 26, and the rod 44 secured to it, reciprocate vertically with the needle-bar 3.

In order to provide for an initial adjustment of the needle in its path of lateral shift, the short link 33 may be adjustable as to length. Further, to enable the length of throw of the needle to be initially adjusted, the point of connection of the link 33 and lever 40 may obviously be made adjustable along the length of the lever.

The function of the attachment may be understood by consideration of Fig. 3. The hook 5 moves in a circular path (of which the effective arc is that above the diameter X'OX) below a slot in the work table 2, through which the needle passes at each stroke. Irrespective of the lateral position of the needle, the stroke is of a constant length a , being determined by the stroke of the needle-bar 3; however, as may be seen from Fig. 3, the upper and lower limits of the stroke a are changed in accordance with every change of position of the pin 30 (which is secured to the needle block 28) in the cam slot 32. In the development of the invention, consideration has shown that the primary function is to bring the needle to such a position at every reciprocation that the loop formed in the upper thread below the base fabric extends across the path of the hook at the time when the hook passes the needle. Preferably, also, the common practice of having the needle past its bottom dead-centre and commencing to rise at the time of engagement of the loop by the hook is to be retained. As a basis for the derivation of the true shape of the cam slot 32, the locus of the lower dead-centres of the needle strokes with various throws might be considered as an arc of radius equal to that of the path of the hook, and vertically below the said path. This, however, neglects the time taken for the rotation of the hook from a datum line OX into the line of reciprocation of the needle dur-

ing a particular stroke. For example, when the pin 30 is at the extreme left of the slot 32, the hook has to rotate from the line OX through the angle c , while for every successive position of the pin 30 towards the right of the slot 32 the angle through which the hook rotates is progressively smaller than the angle c . It has therefore been found desirable to lower the bottom dead-centre of the needle stroke a to a maximum extent b below the path of the hook for the extreme left position of the needle, and to a progressively smaller extent to the extreme right position. Thus, in the extreme left position the time taken for the hook 5 to rotate through the angle c corresponds to the time taken by the needle to rise from its lower dead-centre through the distance b , and the loop in the needle thread is correctly positioned for engagement by the hook; similarly, the times occupied by the rotation of the hook and the rise of the needle are correlated for every position, and perfect engagement of the thread loops by the hook is attained up to the limits of the needle throw, notwithstanding that the length of the said throw may approximate to the diameter of the path of the hook and that at the one extreme the hook is rising practically vertically while at the other extreme the hook is descending practically vertically. For effecting the said lowering of the lower dead-centre of the needle strokes in the positions towards the left, the cam slot 32 is shaped substantially as shown in Fig. 3 of the drawings, being not quite symmetrical about a vertical line, but having its left end lower than its right end. On account of the irregularity caused in the speed of the hook in accordance with the throw of the needle by the mechanism of certain known machines, the decrease in the lowering of the needle may not be exactly uniform from left to right when the invention is applied to such machines. Nevertheless, the shape of the slot 32 is but a slight modification of that shown in Fig. 3. With a cam slot exactly as shown, it is obviously possible to eliminate if desired the mechanism hitherto specially provided for imparting irregularity of speed to the hook, and thus to employ a hook having a uniform speed.

When, according to the invention, the throw of the needle is increased, it is desirable, and may be necessary, to set back, as by grinding or otherwise, the nose of the usual base member (not shown) about which the hook rotates, so that thread loops taken up by the hook, even at the extreme left-hand needle position, may subsequently be transferred to the said nose in the ordinary manner of sewing.

Figs. 4 and 5 show the attachment with the needle at lower dead-centre in its extreme right and left positions respectively. In each case the hook 5 is in its datum position as described with reference to Fig. 3, but it will be observed that in Fig. 4 by virtue of the dropping of the left end of the cam slot 32 the needle block 29 and the needle 29 are lower than in Fig. 5, where the pin 30 is in the higher right end of the cam slot.

As has been mentioned hereinbefore, the known machines of the kind with which the invention is concerned suffer a disadvantage arising from the fact that the thread tension remains unchanged despite variations in the throw of the needle. With the means as hereinbefore described permitting, if desired, an increase in the needle throw, it is even more desirable to avoid any possibility of the tension of the needle thread spoiling the effectiveness of the work of the machine.

The invention therefore contemplates the provision of means for overcoming the disadvantage.

One form of the means suitable for attachment to the existing machines is shown in Figs. 6 and 7. An auxiliary arm 11a is secured to the bell crank lever 11 forming part of the linkage controlling the throw of the needle from the knee-lift lever. The arm 11a actuates a lever 46 through a tie rod 47. Adjustment of the relative positions of the arm 11a and the lever 46 is made possible by forming the rod 47 in two parts slotted at 48 to receive bolts 49. Also, the relative amounts of turning of the arm 11a and the lever 46 are made adjustable by attaching the rod 47 to the arm 11a by means of a pivot 50 engaging a slot 51 in the said arm. The lever 46 is mounted on a pin 52 supported in the body 1 of the machine, and a toothed quadrant 53 is also mounted on the pin so as to be turnable with the lever 46. The quadrant meshes with a toothed pinion 54, the hub of which is screw-threaded internally and engages a screw-thread formed on a pin 55 carrying a pair of conical thread-tension plates or washers 56 and compression control spring 57. In the operation of sewing, a thread 58 passes from a spool or bobbin 59 on the mounting 8 through eyes 60 and 61 in the upper and lateral parts respectively of a wing 62 on the machine head, and thence between the plates 56 of the friction device. Thereafter the thread 30 passes to the usual take-up lever 63 and the needle. It will be evident that, in the controlling of the throw of the needle, as the bell crank 11 is from time to time turned on its pivot, the arm 11a through the linkage 46, 47 and the toothed quadrant 53 will turn the pinion 54, causing it, by reason of its screw-threaded mounting on the pin 55, to move axially on the said pin, thereby decreasing or increasing the pressure of the spring 57 upon the plates 56 and correspondingly changing the tension of the needle thread. The nature of the screw-thread connection should evidently be such that as the needle throw is increased the pinion 54 is moved outwards on the pin 55 to slacken the thread tension, and as the needle throw is decreased the pinion 54 is moved inwards to increase the thread tension.

Fig. 8 shows the complete assembly of a machine, with an attachment for raising and lowering the limits of the needle stroke in accordance with the lateral throwing of the needle block 28 on the plate 24; linkage 33, 40 for obtaining an increased throw of the needle block from the cross-over crank 4 without modifying the mechanism provided in the machine for reciprocating the said crank; and auxiliary arm 11a actuating, through the linkage 46, 47 and the quadrant 53, the pinion 54 which controls the tension of the needle thread.

A modification of the attachment as above described, illustrated in Fig. 9 of the drawings, is fitted with two needles, for sewing patterns in two colours simultaneously or for sewing divided patterns, such as split leaves, in one colour or two colours. The attachment comprises the plate 24 attached to the needle-bar 3, and carrying a second plate 26 having a slide 27 upon which the needle block 28 is vertically movable, the only difference being that the slide 27 is constituted by a central under-cut rib which the block 28 is adapted slidably to embrace. The plate 26 is movable horizontally in the slides 25 by the cross-over crank 4, an extension 4b of which engages the vertical rod 44 by means of a block 43 slidable on the rod. The needle block 28 carries above 75

the needle 29, a pin 30 engaging the cam slot 32 in the plate 24. In addition, the modified attachment carries a second needle block 28a, mounting a needle 29a and slidably supported on 5 the guide 27a of a plate 26a horizontally movable in the slides 25. The plate 26a has a lug 45a supporting a vertical rod 44a, which is slidably embraced by a block 43a pivoted to an additional cross-over crank 4a, whereby the plate 26a is 10 moved in the slides 25. Above the needle 29a, the block 28a also carries a pin 30a engaging the slot 32. The blocks 28 and 28a are adapted for the pins 30, 30a to be brought close together in the slot 32 when necessary, the needles 29, 15 29a also being then close together.

In the machines to which the aforesaid attachments are applicable, for the assistance of the operator in controlling the work and with the means 9 in the position shown in Fig. 6, all the 20 stitches commence from the left-hand edge of the pattern, so that it is only necessary for the base fabric to be moved with the said edge of the pattern under the extreme left position of the needle, the knee-lift lever being operated to control 25 the length of the lateral throw, so that thread is carried on alternate throws to the right-hand edge of the pattern. With the modification having two needles, the operator moves the base fabric to pass the left-hand edge of the pattern 30 under the extreme left position of the left-hand needle, and operates the knee-lift lever to control the length of the joint throw of the needles so that the throw brings the right-hand needle to the right-hand edge of the pattern. Sewing in 35 this manner presents no difficulty, as the operator watches only the total width sewn, the proportions of the respective widths sewn by the two needles being determined by means of suitable linkages of the nature shown in Figs. 1a and 1b, 40 modified as may be required (which form no part of this invention). The respective strokes of the two needles shown in Fig. 9 may be such as to produce a variety of designs. For instance, in the sewing of a split leaf pattern, whether symmetrical or not, the left-hand needle may work that side of the leaf to the left of the vein in one colour, while the right-hand needle works that side of the leaf to the right of the vein in the same or another colour, the movements being so 45 arranged and controlled that, despite such changes of the respective throws as may be necessary to work the broader and narrower parts of the leaf, the central vein is not sewn over. As another example, in the sewing of flower petal 50 patterns, where one colour merges into another, the strokes of the two needles may be made to overlap, since the controlling linkages may be such as to cause the needles to move to the left and to the right simultaneously. In this case, at 55 the juncture of the parts sewn in the two colours there will be a mingling of the threads so that the colours will have an appearance of shading into one another.

From the foregoing it becomes apparent that 60 the invention affords several possibilities of improvement in the art of embroidery or like sewing, by modification of the known machines, namely:—

(a) Increase of needle throw and accuracy 65 throughout the increased range with the hook rotating at the customary irregular speed and therefore without requiring modification of the special mechanism or gearing which rotates the hook;

(b) Increased accuracy over the existing range

of needle throw with elimination of the present special mechanism for rotating the hook at an irregular speed;

(c) Increase of throw, and accuracy throughout the increased range, with elimination of the 5 said mechanism for rotating the hook at an irregular speed.

A new machine incorporating means according to the invention may, of course, be constructed to realize any of the possibilities (a), (b) or (c), and 10 in a new machine fixed bearings (not a swing carrier) may be provided for the needle-bar.

In the constructions hereinbefore mentioned the needle moves vertically, i. e. in its own axis perpendicularly to the plane of the work, regardless of the position it occupies along its path of lateral throw. Such a movement is to be preferred for various reasons, and the possibility of obtaining it by means of the said constructions is an advantage not present in existing machines 20 with swing frame needle-bar carriers, in which the needle has a movement perpendicular to the plane of the work only when it happens to be located at one particular point, such as the midpoint of its lateral throw. At all the other points 25 of the said throw the needle is inclined, more or less, to the plane of the work.

The invention also confers several further advantages. The obvious advantage of being able to execute large patterns (without the necessity 30 for going over the work in a number of strips, or first executing a marginal strip and then "seeding in" the middle portion) itself results in a remarkable increase in the speed at which work may be executed. Apart from this, the absolute 35 certainty with which the hook takes up the needle thread loops, even at the extremes of the lateral throw, prevents waste of time in unpicking and repeating work on account of dropped stitches, and also waste of thread. In the case where ad- 40 vantage is taken to use a hook rotating at uniform speed, the consequent better balance and reduced friction of the moving parts further enables the machine to be operated at an absolute speed much greater than has hitherto been practicable, this speed being limited only by the skill 45 of the operator.

The embroidery machines have been hereinbefore described as having only one hook co-operating with a single needle or a single group of 50 needles. It will, however, be understood that the invention may be applied to machines for special purposes having a plurality of hooks co-operating with a like plurality of needles or groups of needles.

We claim:—

1. In a sewing machine, the combination of 55 means for reciprocating the needle axially, means for throwing the needle to and fro laterally to a variable extent in a plane transverse to the line of sewing, a rotary hook actuatable in timed relationship with the needle reciprocating and throwing means, manually-controlled means for varying the extent of the needle throwing at the will of the operator, and means varying the height at 60 which the needle reciprocates in dependence on the variable lateral throw imparted to the needle and thereby ensuring proper presentation of the needle thread loops to the hook in all of the variable lateral positions of the needle.

2. In a sewing machine, the combination of 65 means for reciprocating the needle axially, means for throwing the needle to and fro laterally to a variable extent in a plane transverse to the line of sewing, a rotary hook actuatable in timed rela- 70

tionship with the needle reciprocating and throwing means, manually-controlled means for varying the extent of the needle throwing at the will of the operator, and means raising and lowering the height of reciprocation of the needle as it is variably thrown laterally, said means causing such change of the height of reciprocation that the time taken for the needle in any line of reciprocation between the limits of variable lateral throw to rise from its lower dead centre to the effective arc of the hook path is equal to the time taken by the hook to reach the line of reciprocation.

3. In a sewing machine, the combination of means for reciprocating the needle axially, means for throwing the needle to and fro laterally to a variable extent in a plane transverse to the line of sewing, a rotary hook actuatable in timed relationship with the needle reciprocating and throwing means, and means raising and lowering the height of reciprocation of the needle as it is variably thrown laterally, said last mentioned means maintaining the needle vertical and causing such change of the height of reciprocation that the time taken for the needle in any line of reciprocation between the limits of variable lateral throw to rise from its lower dead centre to the effective arc of the hook path is equal to the time taken by the hook to reach the line of reciprocation.

4. In a sewing machine, the combination of means for reciprocating the needle axially, a rotary hook actuatable in timed relationship with the needle reciprocating means, means effecting variable lateral throwing of the needle up to an extent substantially equal to the diameter of the hook, means maintaining the needle vertical in all lateral positions, and means ensuring proper presentation of the needle thread loops to the hook in all lateral positions of the needle.

5. In a sewing machine, the combination of means for reciprocating the needle axially, means for throwing the needle to and fro laterally to a variable extent in a plane transverse to the line of sewing, a rotary hook actuatable in timed relationship with the needle reciprocating and throwing means, and cam means connecting the needle-reciprocating means with the needle and serving to vary the height at which the needle reciprocates in dependence on the variable lateral throw imparted to the needle, the cam means ensuring proper presentation of the needle thread loops to the hook in all lateral positions of the needle.

55. 6. In a sewing machine, the combination of means for reciprocating the needle axially, means for throwing the needle to and fro laterally to a variable extent in a plane transverse to the line of sewing, a rotary hook actuatable in timed relationship with the needle reciprocating and throwing means, and pin-and-slot means connecting the needle-reciprocating means with the needle and serving to raise and lower the height of reciprocation of the needle as it is variably thrown laterally, the pin-and-slot means causing such change of the height of reciprocation that the time taken for the needle in any line of reciprocation to rise from its lower dead centre to the effective arc of the hook path is equal to the time taken by the hook to reach the line of reciprocation.

7. In a sewing machine, the combination of means for reciprocating the needle axially, a rotary hook actuatable in timed relationship with the needle reciprocating means, means effecting vari-

able lateral throwing of the needle in a plane transverse to the line of sewing up to an extent substantially equal to the diameter of the hook and cam means connecting the needle-reciprocating means with the needle and serving to ensure proper presentation of the needle thread loops to the hook in all lateral positions of the needle.

8. In a sewing machine, the combination of means for reciprocating the needle axially, means for throwing the needle to and fro laterally to a variable extent in a plane transverse to the line of sewing, a rotary hook actuatable in timed relationship with the needle reciprocating and throwing means, a lever included in the needle-throwing means imparting a multiplied variable throw to the needle, and pin-and-slot means connecting the needle-reciprocating means with the needle and serving to ensure proper presentation of the needle thread loops to the hook in all lateral positions of the needle.

9. In a sewing machine, the combination of means for reciprocating the needle axially, means for throwing the needle to and fro laterally to a variable extent, a rotary hook actuatable in timed relationship with the needle reciprocating and throwing means, manually-controlled means for varying the extent of said needle throwing at the will of the operator, and cam means connecting the needle-reciprocating means with the needle and serving to raise and lower the height of reciprocation of the needle as it is variably thrown laterally, the cam means maintaining the needle vertical and causing such change of the height of reciprocation that the needle reciprocates to lower dead centres which are progressively at a less distance below the effective arc of the hook path as the needle is thrown to successive lines of reciprocation from the end to the beginning of said arc.

10. In a sewing machine, the combination of means for reciprocating the needle axially, a rotary hook actuatable in timed relationship with the needle reciprocating means, means effecting variable lateral throwing of the needle in a plane transverse to the line of sewing up to an extent substantially equal to the diameter of the hook, means maintaining the needle vertical in all lateral positions, and pin-and-slot means connecting the needle-reciprocating means with the needle and serving to impart to the needle as it is moved to successive lines of reciprocation from the beginning to the end of the effective arc of the hook path such changes of height that the needle reciprocates to lower dead centres which are progressively at a greater distance below said arc.

11. In a sewing machine, means comprising in combination a member vertically reciprocable between fixed limits, a rotary hook, a member supported by the said member and laterally movable parallel to the plane of the hook, a needle-holding member vertically movable on the laterally movable member, means imparting variable lateral movements to the laterally movable member, and a pin on the needle-holding member engaging a cam slot associated with the vertically reciprocable member, said pin and slot varying the height at which the needle reciprocates in dependence on the variable lateral movements imparted to the needle, and ensuring proper presentation of the needle thread loops to the hook in all lateral positions of the needle.

12. In a sewing machine, the combination of a rotary hook, a member vertically reciprocable between fixed limits, a member supported by the said member and laterally movable parallel to the

- plane of the hook, a needle-holding member vertically movable on the laterally movable member and a pin on the needle-holding member engaging a cam slot associated with the vertically reciprocable member, with means for effecting variable lateral throwing of the needle up to an extent substantially equal to the diameter of the hook, said cam slot being shaped to impart to the needle as it is moved to successive lines of reciprocation from the beginning to the end of the effective arc of the hook path such changes of height that the needle reciprocates to lower dead centres which are progressively at a greater distance below said arc.
15. 13. In a sewing machine, means comprising in combination a rotary hook, a needle bar vertically reciprocable between fixed limits, lateral guide means supported by the needle bar, a member variably laterally slideable parallel to the plane of the hook on the said guide means, vertical guide means on the said member, a needle block slideable on the vertical guide means, a cam slotted member supported by the needle bar, and a pin on the needle block engaging the cam slot, said slot being shaped to cause such change of the height of reciprocation of the needle that the time taken for the needle in any line of reciprocation to rise from its lower dead centre to the effective arc of the hook path is equal to the time taken by the hook to reach the line of reciprocation.
14. In a sewing machine, the combination of a rotary hook, of a needle bar vertically reciprocable between fixed limits, lateral guide means supported by the needle bar, a member variably laterally slideable parallel to the plane of the hook on the said guide means, vertical guide means on the said member, a needle block slideable on the vertical guide means, a cam slotted member supported by the needle bar, a pin on the needle block engaging the cam slot, and means for effecting lateral throwing of the needle up to an extent substantially equal to the diameter of the hook, said slot being shaped to ensure proper presentation of the needle thread loops to the hook in all lateral positions of the needle.
15. In a sewing machine, the combination of a needle bar vertically reciprocable between fixed limits, lateral guide means supported by the needle bar, a member laterally slideable on the said guide means, means for throwing said laterally slideable member to and fro, a rotary hook actuatable in timed relationship with said needle bar and said throwing means, a multiplying lever included in said throwing means, vertical guide means on the said member, a needle block slideable on the vertical guide means, the lateral guide means having a cam slot, and a pin on the needle block engaging the cam slot, said slot being shaped to ensure proper presentation of the needle thread loops to the hook in all lateral positions of the needle, a vertical extension on the laterally slideable member, and a block member slideable in the extension and pivoted to the lever, throwing movements multiplied by the lever being transmitted through the block member and the extension to the laterally slideable member without hindering the vertical reciprocations of the laterally slideable member.
16. In a sewing machine, means comprising in combination a member vertically reciprocable between fixed limits, needle throwing means, a rotary hook actuatable in timed relationship with said member and said means, a laterally movable member supported by the said member, a needle-
- holding member vertically movable on the laterally movable member and a pin on the needle-holding member engaging a cam slot associated with the vertically reciprocable member, a vertical extension on the laterally movable member, a yoke member slidably embracing the extension, the said yoke member being operatively connected to the needle-throwing means and transmitting needle-throwing movements through the extension to the laterally movable member without hindering its vertical reciprocations, and the said cam slot being shaped to cause such change of the height of reciprocation of the needle as it is thrown laterally that the time taken for the needle in any line of reciprocation to rise from its lower dead centre to the effective arc of the hook path is equal to the time taken by the hook to reach the line of reciprocation.
17. In a sewing machine of the kind set forth and having a take-up lever and an adjacent friction device from which the needle thread passes to said lever, said device controlling the tension of the needle thread, the combination of a knee-lift lever actuatable by the operator to control the extent of the needle throw, spring loading means in said friction device, and means actuatable by the knee-lift lever to relieve said spring loading progressively as the needle throw is increased, and vice versa.
18. In a sewing machine of the kind set forth, the combination of a knee-lift lever actuatable by the operator to control the extent of the needle throw, a take-up lever, a needle thread tensioning device adjacent said take-up lever, from which said thread passes to said lever, comprising a pair of friction members and spring means pressing said members together, an externally screw-threaded member supporting an internally screw-threaded member which abuts said spring means, and lever means operatively connected with said knee-lift lever for turning said internally threaded member and thereby moving it axially to vary the stress in said spring means.
19. In a sewing machine of the kind set forth, the combination of a knee-lift lever actuatable by the operator to control the extent of the needle throw, a thread tensioning device comprising a stud, a pair of conoidal washers supported on the stud, an externally screw-threaded portion on the stud, an internally screw-threaded pinion seated on said portion, a coil spring surrounding the stud and abutting the pinion and one of the washers, a fixed stop abutting the other of the washers, a toothed quadrant meshing with the pinion, and lever means operatively connected with the knee-lift lever for turning the quadrant.
20. In a sewing machine having a plurality of needles, means for reciprocating the needles axially, means for throwing the needles to and fro laterally to a variable extent and a coacting rotary hook, means varying the height at which each needle reciprocates in dependence on the variable lateral throw imparted to it, said means ensuring proper presentation of the needle thread loops to the hook in all lateral positions of the needles.
21. In a sewing machine having a plurality of needles, common means for reciprocating the needles axially, means for throwing the needles to and fro laterally to a variable extent and a co-operating rotary hook, cam means connecting the needles with the common needle-reciprocating means and serving to vary the height at which each needle reciprocates in dependence

on the variable lateral throw imparted to it, said cam means ensuring proper presentation of the needle thread loops to the hook in all lateral positions of the needles.

5 22. In a sewing machine having a plurality of needles, means for reciprocating the needles axially, means for throwing the needles to and fro laterally to a variable extent, and a co-operating rotary hook, pin-and-slot means connecting the needle-reciprocating means with the needles and serving to raise and lower the heights of reciprocation of the needles as they are variably thrown laterally, said pin-and-slot means causing such change of the heights of reciprocation that the time taken for each needle in any line of reciprocation to rise from its lower dead centre to the effective arc of the hook path is equal to the time taken by the hook to reach the line of reciprocation.

20 23. In a sewing machine having a plurality of needles, means for reciprocating the needles axially, and a co-operating rotary hook, the combination of means effecting variable lateral throwing of the needles parallel to the plane of the hook up to a total extent substantially equal to the diameter of the hook, means maintaining the needles vertical in all lateral positions, and pin-and-slot means connecting the needle-reciprocating means with the needles and serving to impart to the needles as they are moved to successive lines of reciprocation from the beginning to the end of the effective arc of the hook path such independent changes of height that the needles reciprocate to lower dead centres which are progressively at a greater distance below said arc.

25 24. In a sewing machine having a plurality of needles and a co-operating rotary hook, the combination of a needle bar vertically reciprocable between fixed limits, lateral guide means supported by the needle bar, a plurality of members laterally slidable on the said guide means, vertical guide means on each of said members, a needle block independently slidable on the vertical guide means on each of said members, a cam slotted member supported by the needle bar, a pin on each of the needle blocks engaging the cam slot, and means for effecting lateral throwing of the needles up to a total extent substantially equal to the diameter of the hook, said cam slot being shaped to ensure proper presentation of the needle thread loops to the hook in all lateral positions of the needles.

30 25. An attachment for a sewing machine having means for reciprocating the needle axially, means for throwing the needle to and fro laterally to a variable extent, and a rotary hook actuatable in timed relationship with the needle reciprocating and throwing means, comprising means raising and lowering the height of reciprocation of the needle as it is variably thrown laterally in a plane transverse to the line of sewing, said means causing such change of the height of reciprocation that the time taken for the needle in any line of reciprocation to rise from its lower dead centre to the effective arc of the hook path is equal to the time taken by the hook to reach the line of reciprocation.

35 26. An attachment for a sewing machine having means for reciprocating the needle axially, means for throwing the needle to and fro laterally to a variable extent, and a rotary hook actuatable in timed relationship with the needle reciprocating and throwing means, comprising in combination a needle-holding member, a lever attachable by pivot means at its upper end to the ma-

chine and by pivot means at its middle to the needle-throwing means and by pivot means at its lower end to the needle-holding member, the pivot means being so located that the needle throwing means impart through the lever a multiplied variable throw to the needle-holding member in a plane transverse to the line of sewing, and pin-and-slot means serving to connect the needle-reciprocating means with the needle-holding member and to ensure proper presentation of the needle thread loops to the hook in all lateral positions of the needle.

40 27. An attachment for a sewing machine having needle-reciprocating means including a needle-bar movable vertically in fixed guides between fixed limits, means for throwing the needle to and fro laterally to a variable extent and a rotary hook actuatable in timed relationship with the needle bar and the needle throwing means, comprising in combination a laterally movable member attachable to the needle-bar, a needle-holding member vertically movable on said laterally movable member and a pin on said needle-holding member engaging a cam slot associated with said attachable member, said cam slot being shaped to vary the height at which the needle reciprocates in dependence on the variable lateral throw imparted to the needle, and to ensure proper presentation of the needle thread loops to the hook in all lateral positions of the needle.

45 28. An attachment for a sewing machine having a plurality of needles, means for reciprocating the needles axially, means for throwing the needles to and fro laterally to a variable extent and a co-operating rotary hook, comprising means having in combination a plurality of laterally movable members attachable to the needle-reciprocating means, a needle-holding member vertically movable on each of said laterally movable members, and a pin on each of the needle-holding members engaging a cam slot associated with said attachable member, in combination with means attachable to the needle-throwing means for effecting lateral throwing of the needles up to a total extent substantially equal to the diameter of the hook, said cam slot being shaped to impart to the needles as they are moved to successive lines of reciprocation from the beginning to the end of the effective arc of the hook path such changes of height that the needles reciprocate to lower dead centres which are progressively at a greater distance below said arc.

50 29. An attachment for a sewing machine having needle-reciprocating means constituted by a needle-bar movable vertically in fixed guides between fixed limits, means for throwing the needle to and fro laterally to a variable extent and a rotary hook actuatable in timed relationship with the needle bar and the needle throwing means, comprising in combination lateral guide means attachable to the needle-bar, a member variably laterally slidable on said guide means, vertical guide means on said member, a needle block slidable on the vertical guide means, the lateral guide means having a cam slot and a pin on the needle block engaging the cam slot, said cam slot being shaped to cause such change of the height of reciprocation of the needle that the time taken for the needle in any line of reciprocation to rise from its lower dead centre to the effective arc of the hook path is equal to the time taken by the hook to reach the line of reciprocation.

55 30. An attachment for a sewing machine hav-

ing means for reciprocating the needle axially, means for throwing the needle to and fro laterally to a variable extent, and a rotary hook actuatable in timed relationship with the needle reciprocating and throwing means, comprising in combination a multiplying lever attachable by pivot means to the machine and to the needle-throwing means, lateral guide means attachable to the needle-reciprocating means, a member laterally slidable on said guide means, vertical guide means on said member, a needle block slidable on the vertical guide means, the lateral guide means having a cam slot, said cam slot being shaped to ensure proper presentation of the needle thread loops to the hook in all lateral positions of the needle, a pin on the needle block engaging said cam slot, a vertical extension on the laterally slidable member, a block member slidable on the said extension and attachable by pivot means to the lever, the said several pivot means being relatively located by the lever in such manner that needle-throwing movements are multiplied by the lever, said movements being transmissible through the block member and the extension to the laterally slidable member without hindering the vertical reciprocations of the laterally slidable member.

31. An attachment for a sewing machine having needle-reciprocating means including a needle bar vertically reciprocable between fixed limits, means for throwing the needle to and fro laterally to a variable extent, and a co-operating rotary hook, said attachment comprising in combination a plate attachable to the lower end of the needle bar transversely to the line of feed of the machine, horizontal slides on said plate, a member transversely movable in said slides, a rod extending vertically upwards from said member, a yoke slidable on said rod and pivotally attachable to the needle-throwing means, vertical slides on said member, a needle block vertically movable in said vertical slides, a pin projecting rearwardly from said needle block, a vertical slot

in said member, and a cam slot in said plate, said pin projecting through said vertical slot and co-operating with said cam slot, which is shaped to impart to the needle block as said member and said needle block are moved laterally by the needle-throwing means through said rod and yoke such changes of height of reciprocation that the time taken by a needle secured in said blocks to rise from its lower dead centre in any line of reciprocation to the effective arc 10 of the hook path is equal to the time taken by the hook to reach the line of reciprocation. 5

32. In a sewing machine, the combination of means for reciprocating the needle axially, a rotary hook actuatable in timed relationship with 15 the needle reciprocating means, means actuatable in timed relationship with the needle reciprocating means and the hook for variably throwing the needle to and fro laterally up to an extent substantially equal to the diameter of the 20 hook, and means ensuring proper presentation of the needle thread loops to the hook in all lateral positions of the needle.

33. In a sewing machine, the combination of needle reciprocating means, means effecting 25 variable lateral throwing of the needle, a rotary hook actuatable in timed relationship with said needle reciprocating and throwing means, manually operable means controlling the lateral throwing of the needle up to an extent substantially equal to the diameter of the hook, means 30 ensuring proper presentation of the needle thread loops to the hook in all lateral positions of the needle, a take-up lever, a friction device adjacent said lever from which said thread 35 passes to said lever, and means automatically varying the pressure of said friction device and consequently the tension of the needle thread with the manually controlled variable extent of the throw of the needle. 40
